[57] CLAIM

The ornamental design for a ventilated boot, as shown and described.

DESCRIPTION

FIG. 1 is a front and left side perspective view of a ventilated boot showing my new design;

FIG. 2 is a right side elevational view thereof;

FIG. 3 is a left side elevational view thereof;

FIG. 4 is a rear elevational view thereof;

FIG. 5 is a front elevational view thereof; and,

FIG. 6 is a top plan view thereof.

The broken line showing of an in-line chassis and laces in FIG. 1 is for illustrative purposes only and forms no part of the claimed design.

FIG. 1

FIG. 2

FIG. 3

FIG. 4

FIG. 5

FIG. 6
